UNITED STATES PATENT OFFICE.

CARL HOFFMAN, OF ALLENTOWN, PENNSYLVANIA.

LOCK DEVICE FOR DOORS.

Application filed October 9, 1922. Serial No. 593,281.

To all whom it may concern:

Be it known that I, CARL HOFFMAN, a citizen of the United States, residing at Allentown, in the county of Lehigh and 5 State of Pennsylvania, have invented certain new and useful Improvements in Lock Devices for Doors; and I do hereby declare the following to be a full, clear, and exact description of the invention, such as will 10 enable others skilled in the art to which it appertains to make and use the same.

My invention relates to locking devices for doors and more particularly to door bolts, an important object of the invention 15 being to provide a simple and efficient bolt for locking the door in a partially opened position as well as when fully closed, the improved device including means whereby the bolt may be coupled with a mechanism 20 for retracting it from its locking position when the door is closed by means of a key from the opposite side of the door.

In the drawings, Figure 1 is a front elevation of a portion of a door and its casing 25 with my improved lock in position for locking the door fully closed and coupled with key controlling means opening it from the outside. Figure 2 is a similar view but with the bolt disengaged from the key controlling means. Figure 3 is a view showing 30 the lock in position for holding the door partially opened, parts being in section. Figure 4 is a sectional view on line 4—4, Figure 1. Figure 5 is a detail of the coupling between the key mechanism and the door bolt.

My improved device includes a casing 1 40 appropriately secured to the door and having a slideway 2 for a spring controlled bolt 3 which has at one end a latch head 4 with a laterally projecting stud 5 and at its other end this bolt is bent at right angles to itself, as at 6, being preferably provided with a head 7, which with such right angular portion forms a handle for operating the bolt.

At 10 I have shown a keeper which is part 45 of the striker plate 12 and with which keeper the latch head 4 engages for locking the door in fully closed position. Outstanding spaced apart ears 13 formed on the 50 plate 12 constitute the support for an auxiliary keeper 14 which is shaped from a single piece of metal bent back upon itself so as to form a loop, its ends being pivoted to the ears. The bowed portion of this keeper has 55 a slot 15 to receive the stud 5 of the latch

head 4, engagement between the stud and the wall at the end of the slot preventing retraction of the latch head from locking position when the door is partially opened 60 as shown in Figure 3.

A means by which the bolt may be operated from outside the door when positioned for that purpose includes a lock mechanism such as is conventionally shown 65 at 21 in Figure 3 and which is preferably of the cylinder type, with a coupling. This coupling includes a base plate 22 which is connected by screws 23 through part of the lock and serves as means for retaining the 70 whole in position. The base plate has a central aperture which receives the rearwardly projecting screw threaded post 24 of a rotatable plate 25, a nut 26 holding the rotatable plate in position on the base plate. The post of the rotatable plate is bifurcated, 75 as at 27, to receive the stem 28 of the lock mechanism. The rotatable plate 25 has a single aperture 29 of slightly larger diameter than the head of the screws 23, this aperture forming the means by which access is had to the screw holes 22 for placing the lock mechanism and in the normal position of the parts the aperture of the rotatable plate lies away from both the screw holes 80 of the base plate. When access is to be had to the screws the rotatable plate must be turned first in one direction and then in another (see the arrows in Figure 2) so that one screw at a time is in line with this 85 aperture. Integrally formed with the rotatable plate to one side of its center and extending at right angles thereto is a wing 30. When the right angular handle 6 of the bolt is in its normal position it will lie in 90 parallelism with and adjacent to the wing 30, its spring tending to hold it in this upright position so that any turning movement of the rotatable plate will cause a retraction of the bolt through the action of 95 the wing on the handle.

In operation, with the parts in the position shown in Figure 1, the door is closed and locked, the latch head 4 engaging the keeper 10, and the handle 6 being in engagement with the wing 30. Turning of the rotatable plate 25 through the instrumentality of a key inserted in the lock mechanism will effect a retraction of the latch, permitting opening of the door. Manifestly 100 the bolt may be readily withdrawn from locking position from the same side of the 110

door on which it is placed by pressure applied to the handle 6. The spring which acts to hold the bolt outwardly also serves to normally maintain the handle 6 in engagement with the wing 30. If it be desired to use the latch as a dead lock, the handle 6 is turned downwardly as shown in Figure 2, and firmly held in this downward position by a button 31 having a hooked portion which lies over the handle, the button being rotatably supported by the casing. When so positioned turning of the rotatable plate is ineffective as a means for retracting the latch. Doors are frequently left ajar for ventilating or other purposes, and my improved lock is adapted to hold a door in such partially opened position and to lock it against unauthorized opening. The auxiliary keeper 14 is turned on its pivot to the position shown in Figure 3, and the bolt is turned from the normal position with its handle upstanding to that where it is directly opposite which brings about engagement between stud 5 and the wall of the slot 15. The handle 6 is thus held to its position by the button 31. So placed, the bolt acts to hold the door in the partially opened position and locks it so that it cannot be opened from the outside.

30 I claim as my invention:

1. A fastening device for a door including a rotatable sliding bolt, a keeper with which said bolt engages, a key operated mechanism, and means adaptable upon rotation of the bolt for coupling said bolt and said key operated mechanism at will to permit retraction of the bolt from said keeper by manipulation of said key mechanism.

2. A fastening device for a door including a sliding spring actuated bolt, a keeper with which said bolt engages, a key operated mechanism, means rendered effective by the spring actuated character of said bolt for normally coupling said bolt and said key operated mechanism, and means for rendering said last mentioned means ineffective.

3. A fastening device for a door including a sliding spring actuated bolt, a keeper with which said bolt engages, a key operated mechanism, and rotatable means normally coupling said bolt and said key operated mechanism, and a member for engaging and holding said bolt to render said coupling means ineffective.

4. A fastening device for a door including a spring actuated bolt, a keeper with which said bolt engages, a key operated

mechanism, a rotatable plate coupled with said key mechanism and having a wing, means whereby said wing and said bolt may be coupled for operation of said bolt by said key operated mechanism, and a member cooperating with said last mentioned means to prevent coupling between said means and said wing.

5. A fastening device for a door including a sliding spring actuated bolt, said bolt having a right angular portion, a keeper with which said bolt engages, a key operated mechanism, a rotatable plate coupled with said key mechanism and having a wing designed to engage said right angular portion of said bolt to withdraw said bolt when said key operated mechanism is manipulated, said right angular portion being disengagable from said wing and a button cooperating with said right angular portion when the latter is disengaged from said wing.

6. A fastening device for a door including a sliding and rotatable spring actuated bolt, said bolt having a right angular portion, a keeper with which said bolt engages, a key operated mechanism, a rotatable plate having a centrally disposed bifurcated post on one side and a wing on its opposite side, said wing being designed to engage said right angular portion of said bolt when the latter is rotated in one direction, means connecting said rotatable plate and said key operated mechanism comprising a base plate having an aperture through which said post extends, and screws connecting said base plate with said key mechanism, said rotatable plate having an aperture through which access may be had to said screws, and a button for engaging and holding said right angular portion when the latter is disengaged from said wing.

7. A fastening device for a door including a rotatable sliding bolt, a keeper with which said bolt engages, a key operated mechanism, means adaptable upon rotation of the bolt for coupling said bolt and said key operated mechanism at will to permit retraction of the bolt from said keeper by manipulation of said key mechanism, and means independent of said key operated mechanism and its bolt coupling means for rendering said last mentioned means ineffective.

In testimony whereof I have signed this specification.

CARL HOFFMAN,
